ABSTRACT OF THE DISCLOSURE

This invention has for its object a vacuum closure adapted for containers with one open end. Said closure is provided with means for reducing the pressure of air in the containers which use such closure.

BACKGROUND OF THE INVENTION

This invention relates to a vacuum closure for open ended containers. Such closure by reducing the pressure of air within said containers is particularly useful when the latter are to contain air-sensitive materials, more particularly food.

SUMMARY OF THE INVENTION

According to this invention, a vacuum closure for containers having one open end consists in a cap provided with means for reducing the pressure of air therein at least for a substantial period of time. More particularly said cap has a part thereof accommodating sealingly the lips of the container's open end and another part thereof enclosing a plunger slidably mounted therein, outlet means for the air located in the space enclosed by said plunger and said other part, and locking means for maintaining the plunger in the position wherein a maximum amount of air is expelled from said other part. In a preferred embodiment of the invention, said cap has a lower part accommodating sealingly the lips of the container's open end and an upper part thereof enclosing a plunger slidably mounted therein between a lowermost position adjacent to said lower part and an uppermost position, said upper part having a side wall and an upper wall, the latter forming the top of said cap, said upper wall having an outlet aperture for air expelled by upward movement of said plunger, said upper wall also having a seal for hermetically closing said upper part of said cap when said plunger is in said uppermost position, said cap further having means for locking said plunger in said uppermost position.

DETAILED DESCRIPTION OF THE INVENTION

Preferred embodiments of the present invention are described hereinafter by way of example, referring to the accompanying drawings wherein:

FIG. 1 is a sectional view of a first embodiment of closure according to this invention on an open-ended container, said closure having a plunger in lowermost position;

FIG. 2 is a sectional view similar to FIG. 1 but showing the plunger locked in uppermost position;

FIG. 3 is an enlarged view partly in side elevation and partly in section of a hinge connection between piston rod and plunger of the embodiment shown in FIGS. 1 and 2;

FIG. 4 is a sectional view of a second embodiment of closure according to this invention on an open-ended container, said closure having a plunger in lowermost position;

FIG. 5 is a sectional view similar to FIG. 4 but showing the plunger locked in uppermost position, and

FIG. 6 is a partly perspective, partly sectional view showing the plunger locked in the upper wall of the closure.

2

Preferably, a vacuum closure according to this invention, adapted for containers having one open end, comprises a cap 1 having a lower part 2 accommodating sealingly (by means of a seal 3) the lip 4 of a container's open end 5, and an upper part 6 enclosing a plunger 7 slidably mounted therein, between a lowermost position (shown in FIG. 1) adjacent to said lower part 2 and an uppermost position (shown in FIG. 2). Said upper part 6 has a side wall 8 and an upper wall 9, the latter forming the top of said cap. Said upper wall 9 has an outlet aperture 10 for air expelled by upward movement of said plunger 7. It should be understood that the plunger's side wall makes contact so intimately with the side wall of the upper part 6 that expelled air cannot escape between said side walls. Said upper wall 9 also has a seal 11 for hermetically closing said upper part 6 when said plunger 7 is in said uppermost position (shown in FIG. 2).

In a first more preferred embodiment of this invention, the plunger 7 is hingedly connected to one end of a piston rod 12 whose other end extends with clearance through said outlet aperture. In the uppermost position shown in FIG. 2, the piston rod 12 is pivoted so as to lie flat on the upper wall's outer face. As shown, said upper wall's outer face has a radially extending groove 14 for accommodating said piston rod when the latter is lying flat on said face. In addition, a latch 15 is provided for locking the piston rod 12 in its position within the groove 14. The piston rod 12 has a grip portion 16 which extends perpendicularly thereto and is received, in said uppermost position of the plunger, in an extension 17 of the groove provided in the outer face of the side wall 8.

FIG. 3 shows the hinge connection of the piston rod 12 to the plunger 7. Said hinge connection comprises a ball 18 fixed to the plunger 7. A recess (not shown) of the ball 18 receives one end of the piston rod 12 which is pivoted therein by means of a pivot 19.

A second preferred embodiment of this invention is shown in FIGS. 4-6 in which like reference numerals designate parts equivalent or similar to those shown in FIGS. 1-3.

The differences with respect to the first embodiment shown in FIGS. 1-3 consist in the fact that the plunger 7 has a base wall 20 carrying an inner grip portion 21 and an outer portion 22. The grip portion 21 has a handle bar 23, a finger-receiving recess 24 and a side wall 25 with threads 26 adapted for engaging threads 27 of an enlarged outlet aperture 10. The outer portion 22 of the plunger 7 has a side wall 28 adapted for engaging the inner face of the upper part's side wall 8 in such a way that upward movement of the plunger 7 expels air only through the outlet aperture 10. When the plunger 7 is lifted high enough, the threads 26 engage the threads 27 and the plunger may then be screwed within the aperture 10, and locked in its uppermost position as shown in FIG. 5.

I claim:

1. A vacuum closure for containers with one open end, which consists in a cap provided with means for reducing pressure of air therein, said pressure-reducing means comprising an imperforate plunger exposed to the interior of the container and movable in slidably sealed relation to enlarge the internal volume of the container, said cap having a part thereof accommodating sealingly the lips of the container's open end and another part thereof enclosing said imperforate plunger slidably mounted therein, outlet means for the air located in the space enclosed by said plunger and said other part, and locking means for maintaining the plunger in the position wherein a maximum amount of air is expelled from said other part.

2. A vacuum closure for containers with one open end, which consists in a cap provided with means for reducing pressure of air therein, said pressure-reducing means

comprising an imperforate plunger exposed to the interior of the container and movable in slidably sealed relation to enlarge the internal volume of the container, said cap having a lower part accommodating sealingly the lips of the container's open end and an upper part thereof enclosing said imperforate plunger slidably mounted therein between a lowermost position adjacent to said lower part and an uppermost position, said upper part having a side wall and an upper wall, the latter forming the top of said cap, said upper wall having an outlet aperture for air expelled by upwards movement of said plunger, said upper wall also having a seal for hermetically closing said upper part of said cap when said plunger is in said uppermost position, said cap further means for locking said plunger in said uppermost position.

3. A vacuum closure as in claim 2, wherein said plunger is hingedly connected to one end of a piston rod whose other end extends with clearance through said outlet aperture, said piston rod being, in said uppermost position, pivotable so as to be positioned flat on the upper wall's outer face, means being provided for locking said piston rod when the latter is lying flat on said face.

4. A vacuum closure as in claim 3, wherein said upper wall's outer face has a radially extending groove for accommodating said piston rod when the latter is lying flat on said face and a latch is provided for locking said piston rod in its position within said groove.

5. A vacuum closure as in claim 4, wherein said piston rod has a grip portion extending perpendicularly thereto and said groove further extends in the outer face of said upper part so as to accommodate said grip portion in said uppermost position of the plunger.

6. A vacuum closure as in claim 2, wherein said plunger has a grip portion integral therewith, means being provided for locking said grip portion to said upper wall when said plunger is in said uppermost position.

10 7. A vacuum closure as in claim 6, wherein said plunger's grip portion has threads which engage threads of said upper wall's outlet aperture when said plunger is lifted high enough for locking said plunger in said uppermost position.
